ADVERTISING DEVICE

Carrol R. Wooten, New York, N. Y., assignor to
 Beech-Nut Packing Company, Canajoharie,
 N. Y., a corporation of New York

Application October 27, 1939, Serial No. 301,598

8 Claims. (Cl. 40—126)

The present invention relates to toy devices, and has special reference to such devices which may be used in toy circuses and the like for advertising purposes, and has for its object to provide novel and improved devices of this character.

The preferred embodiment of the invention is illustrated, by way of example, in the accompanying drawings, in which:

Figure 1 is a front view of a portion of the 10 device;

Fig. 2 is a sectional plan view, taken substantially on the line 2—2 of Fig. 1;

Fig. 3 is a sectional elevation on an enlarged scale, taken substantially on the line 3—3 of 15 Fig. 1;

Fig. 4 is a sectional elevation, partly broken away, taken on the line 4—4 of Fig. 3;

Fig. 5 is a sectional plan view, partly broken away, taken on line 5—5 of Fig. 1;

Fig. 6 is a detail sectional view, taken on the line 6—6 of Fig. 4;

Fig. 7 is a detail sectional plan view of one of the figures;

Fig. 8 is a sectional elevation, taken on the 25 line 8—8 of Fig. 7;

Fig. 9 is a sectional elevation of the fluid control mechanism for operating the figures;

Fig. 10 is a plan view of the same; and

Fig. 11 is a diagrammatical view of the electric circuit connections with the device.

The device illustrated in the drawings comprises swings 2 which may be in the form of trapeze mounted to swing toward and from each other and figures 4 in representation of trapeze performers secured on the free ends or cross-bars 6 of the trapeze. Each figure 4 has extended arms 8 that are adapted to be swung toward and from each other to cause the hands 10 thereof to grasp and hold an article 11 which may be representative of a five cent package of chewing gum or other article it is desired to advertise.

The arms 8 may be operated in proper timed relation at the limit of the swinging movements of the trapeze toward each other whereby the article 11 held by the arms or hands of one figure is gripped and held by the hands of the other figure, the first figure releasing the article so as to cause the article to be passed from one figure to the other.

In the specific construction shown, the passing of the article from one figure to the other occurs every third back and forth swinging move-

ment of the trapeze, but such timing may be varied as desired.

The cross-bar 6 of each trapeze may be made hollow (Fig. 3) and connected at its ends through tubular rods 12 with a tubular pivot rod 14 which is pivoted in bearings 16 secured to a suitable depending supporting frame 18.

Each swing or trapeze 2 is adapted to be swung by means of an arm 20 having one end secured to the pivot rod 14 and its other end connected by a link 22 with a crank arm 24 secured on a shaft 26. The shaft 26 is mounted to turn in bearings in the lower ends of depending brackets 28, the two arms 24 being secured at the ends of the shaft 26 outside of the brackets 28. A sprocket wheel 30 is secured on the shaft 26 between the brackets 28, which sprocket wheel is driven through a chain 32 and a sprocket wheel 34 from the shaft of an electric motor 38.

With this construction upon rotation of the sprocket wheel 30, the swings or trapeze 2 are swung toward and from each other predetermined distances.

Each figure 4 is secured to the cross-bar 6 of one of the swings with the body and arms of the figure extending outwardly from the cross-bar as shown. The figure may be made of soft rubber. Within each figure there is a supporting plate 40 upon which is pivotally mounted two levers 42, the forward portions of which extend through the arms of the figures and at the outer ends or hands of the arms the ends of the levers project forming gripping surfaces 44. By swinging the levers 42 in opposite directions the arms 8, and consequently hands 10 of the figure, may be moved toward and from each other.

The hands of the figure are pressed from each other by means of a coil spring 46 connecting the inner ends of the levers 42.

Mounted on the supporting plate 40 of each figure between the inner arms of the levers 42 is a cylinder 48 within which are piston heads 50, the outer sides of which engage projections 52 on said arms of the levers 42, the outer movement of the piston heads being limited by caps 54 screw-threaded on the ends of the cylinder 48. Also, on the inside of the cylinder are flanged rubber disks 56 which are held against the piston heads 50 by means of a light coil spring 58.

Extending from the interior of the cylinder 48 are two metal tubes 60 and 62. The tube 60 is an air bleed tube for the cylinder and leads into a passage 64 in the cross-bar 6 of the trapeze, the outer end of the passage 64 being adapted to

be opened and closed by means of a screw 66. The tube 62 leads into a passage 68 in the cross-bar 6, this passage being separated from the passage 64 by a plug 70. The figure 4 may be secured to the cross-bar 6 by welding the tubes 60 and 62 thereto. The passage 68 leads through one of the depending tubes or rods 12 of the trapeze and through the tubular pivot rod 14 to the rear end thereof. Leading from said end of the two pivot rods are flexible tubes 72 which respectively lead into fluid-containing boxes 74 (Fig. 9).

Each fluid box 74 is provided with a cylinder and a piston 76, the piston being connected through a rod or link 78 with a bell-crank 80 pivoted on a pin 82 supported by bracket arms extending from a side of the fluid box 74. The bell cranks 80 are pressed in a direction to retract the pistons by means of a coil spring 84 connecting the outer arms of the bell cranks, the spring passing over a sheave 86.

Each bell crank 80 is adapted to be turned to move its associated piston inwardly by means of a solenoid comprising an electric coil 88 and a core 90.

With this construction, when one of the coils 88 is energized the bell crank lever 80 moves its associated piston 76 inwardly and thus by fluid pressure moves the pistons 50 of the fluid cylinder 48 outwardly to cause the arms 44 of the figure to move inwardly as shown in full lines in Fig. 7.

Upon the coil 88 of one solenoid being de-energized, the spring 46 acts to spread the arms of the Figure 4 associated therewith. Upon the coil 88 of the other solenoid being energized the arms of the figure associated therewith are moved inwardly.

In the illustrated construction, the arms of the two figures are thus operated in predetermined timed relation with each other and with the operation of the trapeze 2 so that at every third back and forth swinging movement of the trapeze when they are at the limit of their movement toward each other, the arms 8 of one figure grasps the article 11 and at the same time the arms of the other figure release the article. Thus the article is passed from one figure to the other at predetermined intervals during the operation of the trapeze 2. To assist the gripping members or hands of the figures to be properly positioned and to effectively hold the article, the sides of the end portions of the article are provided with grooves 92 which receive the ends or hands 10 of the arms of the figures as the hands close on the article.

The coils 88 of the solenoids are energized and de-energized in proper timed relation to thus cause the article to be passed from one figure to the other, through suitable electrical connections which are timed by means of a star-wheel 94. The star-wheel is operated by means of a pin 96 which constitutes the pivotal connection between one of the crank arms 24 and trapeze operating rod or link 22. During each revolution of the sprocket wheel 30, the pin 96 engages one of the arms of the star-wheel 94 and rotates the star-wheel one third of a revolution. As the star-wheel completes substantially one revolution, an arm 98 thereon strikes the movable member of a switch 100 which closes the circuit connection with a relay 102 that acts through a pawl 103 to move a ratchet wheel 104 the distance of one tooth. Ratchet wheel 104 is part of a common control box or timing device which when the ratchet wheel is thus operated moves an arm 106

of a switch to close a circuit connection with one or the other of switch contacts 108 and 110, the circuit connections being alternately opened and closed. When the circuit connection with the switch contact 108 is closed, as shown in Fig. 11, a relay 112 is operated to close the circuit connection with one of the solenoids 88. When the circuit connection with the contact 110 is closed, this solenoid is de-energized and a relay 114 acts to close the circuit connection with the other solenoid 88.

With this construction and arrangement, the figures 14 pass the article 11 alternately from one figure to the other in a remarkably life-like manner and without interruption of the swinging movement of the trapeze, this occurring at the completion of each three back and forth swinging movement of the trapeze.

As will be evident to those skilled in the art, my invention permits various modifications without departing from the spirit thereof or the scope of the appended claims.

What I claim is:

1. In a device of the class described, devices 25 in the form of swings or trapeze mounted to swing predetermined distances in opposite directions toward and away from each other, a figure in simulation of a trapeze performer carried by the free end of each of said swings, each of said 30 figures having arms adapted to be swung toward and away from each other to grip and release an article positioned between them, the article being adapted to be gripped and held by the arms of either figure, and means for operating the arms of the two figures in timed relation when the trapeze devices are at the limit of their swinging movement toward each other whereby said article held by the arms of one of said figures is gripped and held by the arms of the other figure while the arms of the first mentioned figure release the article.

2. In a device of the class described, a device 45 in the form of a swing or a trapeze adapted to swing a predetermined distance, a toy figure carried by the free end of the trapeze, said figure having arms adapted to be swung toward and from each other, and means for thus swinging said arms toward each other when the swing reaches the limit of its movement in one direction, and for opening said arms when the swing reaches said limit of its movement during a subsequent swinging movement thereof.

3. In a device of the class described, devices 55 in the form of swings mounted to swing predetermined distances in opposite directions toward and away from each other, a toy figure mounted on the free end of each of said swings, each of said figures adapted to grip and hold an article when presented thereto in a predetermined position, and means for operating said figures at the limit of the movement of the swings toward each other to cause the article held by one of said figures to be released therefrom and to be gripped and held by the other figure.

4. In a device of the class described, two toy 60 figures each of said figures having arms adapted to be swung toward and away from each other to grip and release an article positioned between them, means for moving the figures to cause the article being held by the arms of one figure to be positioned between the arms of the other figure, and means for moving the arms of the second figure to grip and hold the article and to move the arms of the first figure to release 65 the article.

5. In a device of the class described, a toy figure made of soft rubber or other flexible material having extended arms, levers pivotally mounted within the body of the figure and extending within and lengthwise of said arms, spring means tending to swing said levers to move said arms away from each other, and fluid operable means for swinging said levers to move the arms toward each other against the tension of said spring means.

6. In a device of the class described, devices mounted for movement predetermined distances toward and from each other, a toy figure carried by each of said devices, each of said figures having arms adapted to be swung toward and away from each other to grip and release an article positioned between them, the article being adapted to be gripped and held by the arms of either figure, and means for operating the arms of the two figures in timed relation when said figure carrying devices are at the limit of their

movement toward each other, whereby said article held by the arms of one figure is gripped and held by the arms of the other figure, while the arms of the first figure release the article.

5 7. In a device of the class described, devices in the form of swings mounted to swing predetermined distances toward and away from each other, a figure in simulation of a trapeze performer carried by the free end of each of said swings, each of said figures having movable arms, and means for operating the arms of the two figures in timed relation without interruption of the swinging movement of the swings.

10 8. A structure according to claim 7 in which the means for operating the arms comprises fluid operable means mounted in the body of each figure, and a common means is provided for controlling the operations of the fluid operable means of the two figures.
